UNITED STATES PATENT OFFICE.

ALBERT M. PLIMPTON, OF HORNELLSVILLE, NEW YORK.

VEHICLE-SEAT.

SPECIFICATION forming part of Letters Patent No. 292,945, dated February 5, 1884.
Application filed December 8, 1883. (No model.)

To all whom it may concern:

Be it known that I, ALBERT M. PLIMPTON, a citizen of the United States, residing at Hornellsville, in the county of Steuben and State of New York, have invented certain new and useful Improvements in Vehicle-Seats, of which the following is a specification, reference being had therein to the accompanying drawings.

10 Figure 1 is a perspective, Fig. 2 an end elevation with end-boards removed, and Fig. 3 a partial plan with back-board in dotted lines, of a seat constructed in accordance with my invention.

15 Like letters refer to like parts in all the figures.

The object of my invention is to produce, at a minimum expense, a seat-corner which shall be strong, serviceable, and neat in appearance, and which shall require no external fastening devices at the inner or outsides of the end and back boards.

By the construction hereinafter set forth I am enabled to secure the object mentioned in seats made of light or thin material, the joints at the corners being such that great strength is secured independently of the thickness of the material within certain limits.

20 A represents the bottom, which may be a single board or a frame and panel, as indicated in Fig. 3, the board or frame being beveled at its edges to agree with the desired slant of the back and end boards, B and C, respectively, between which is formed a miter-joint, a.

25 In the ends of the back and end boards, B C, I insert dowel-pins b, which are arranged to project at right angles to the surfaces of the miter, and which are secured by glue, in the usual manner. Screws or other suitable means are employed to secure the end and back boards to the bottom, and being inserted from the under side, as shown by dotted lines, no marring of the outer surfaces occurs, whereby a neat and uniform finish can be given to the entire exposed surfaces of the seat.

To re-enforce the dowel-pins and to give increased strength to the seat as a whole, I employ corner-irons D, which at their ends are turned down to form flanges or points d, which are forced into the upper edges of the

back and end boards. The flanges or points d may be disposed angularly across the upper edges of the end and back boards, so that the outer edge of the corner-iron shall be longer than its inner edge, as shown at the left of Fig. 1, or so that the inner edge shall be the longest, as shown at the right of Fig. 1. In either case the flanges tend to resist separation of the joint a, but more strongly when the inner edge of the corner-iron is longer than the outer, as the flange is disposed parallel with the face of the joint and at a right angle to the dowel-pins. This latter disposition of the flanges is, therefore, preferable in cases where greater strength is desired.

Additional points, d', (dotted lines, Fig. 2,) may be formed on the under surface of the corner-iron, if desired, so that when drawn snugly to place by the screws d'' said points will penetrate the upper edges of the end and back boards and give additional firmness to the parts.

It is apparent that my corner-irons may be employed without the dowel-pins, and therefore I do not limit myself in this respect, but may vary the construction of my seat in such respect and in any other within the skill of persons conversant in the construction of vehicles and seats therefor.

Having described my invention, what I claim as new, and desire to secure by Letters Patent, is—

1. The combination of the bottom-board A, beveled as desired, the back-board B and end-boards C, miter-jointed to each other, the dowel-pins b, projecting at right angles to said joint, and the corner-irons D, having the flanges d embedded in the upper edges of said back and end boards, substantially as shown and described.

2. The combination of the back-board B and an end-board, C, with a corner-iron, D, having downwardly-extending and diagonally-disposed flanges d, substantially as shown and described.

In testimony whereof I affix my signature in presence of two witnesses.

ALBERT M. PLIMPTON.
